[57] ABSTRACT

Books to be jacketed are fed in open position and in a first direction to an assembly station where the covers of a freshly arrived book enter between the central panel and the flaps of a prefabricated jacket which is transported to the assembly station in a second direction counter to the first direction. The feed of books is interrupted in response to an interruption of the transport of jackets, or vice versa, and each book is inspected prior to being fed to the assembly station in order to determine whether or not the end papers adhere to the respective covers. The jackets are prefabricated from rectangular blanks which are withdrawn from a stack and are folded by pairs of coating mechanical folding devices at least one of which is heated to provide each jacket with permanent creases in regions where the flaps adhere to the central panel. Jacketed books are closed and descend into a channel or directly onto a conveyor from which they can be removed by hand for stacking at one or both sides of the assembly station.

**METHOD AND APPARATUS FOR APPLYING
JACKETS TO COVERS OF BOOKS OR THE LIKE**

BACKGROUND OF THE INVENTION

The present invention relates to a method and apparatus for applying jackets to books, brochures, catalogs or the like, and more particularly to a method and apparatus for automatic application of jackets to commodities generally known as or resembling books and having two hard or soft outer covers and a number of leaves or sheets disposed between and riveted, pasted or otherwise secured to the covers.

German Offenlegungsschrift No. 2,008,135 discloses a method and apparatus for automatic application of jackets to books. The books are fed seriatim to a position above a jacket which is provided with two partially folded flaps. One cover of a book which is held in such position is then opened by means of suction cups and the respective flap is folded thereover. In the next step, the book is inverted to expose the other cover and the latter is opened by suction cups to allow for folding of the other flap before the other cover is closed.

A drawback of such method and apparatus is that the system for controlling the deformation of successive jacket blanks, the transport and manipulation of jackets, as well as the transport and manipulation of books are too complex and prone to malfunction, and that the conversion from jacketing of one type or size of books to jacketing of another type or size of books consumes too much time and necessitates several complex adjustments. Still further, the jacketing operation must be preceded by an inspection of books which normally takes place at a location remote from the jacketing apparatus. The inspection involves determining whether or not the free end papers of a book adhere to papers which overlie the inner sides of the covers.

SUMMARY OF THE INVENTION

An object of the invention is to provide a novel and improved apparatus for applying jackets to books in such a way that the application of jackets is incidental to another operation which is to be performed before the books are ready for shipment to stores, schools, libraries or other institutions.

Another object of the invention is to provide an apparatus wherein the books can be jacketed at the same rate at which they pass the final inspection including a determination whether or not the end papers adhere to the respective covers.

A further object of the invention is to provide an apparatus which can be rapidly converted for jacketing of differently dimensioned books and which is simpler, more compact, more reliable and more versatile than heretofore known apparatus.

An additional object of the invention is to provide an apparatus whose jacketing operation is reproducible with a high degree of accuracy and which can furnish jacketed books in an optimum position or orientation for further processing, such as the introduction of jacketed books into boxes or other types of receptacles.

Still another object of the invention is to provide a novel and improved method of manipulating jackets prior to, during and subsequent to folding around the covers of books.

A further object of the invention is to provide a book jacketing method which can be practiced substantially simultaneously with the customary final inspection of

books for determining the condition of their end papers.

The method of the present invention involves the application of jackets to covers of books or similar commodities (hereinafter called books), and comprises the steps of converting successive preferably rectangular sheet-like blanks into jackets each including a central panel and two flaps which at least partially overlap the panel, moving successive jackets to an assembly station along a first path, opening successive books so that their covers are spaced apart from the leaves, moving the thus opened books to the assembly station along a second path so that portions of the covers of a book enter between the panel and the flaps of a jacket at the assembly station, and closing the thus jacketed book so that the flaps of the respective jacket are located between the covers and the leaves of the closed book.

The jackets which are moved along the first path preferably advance counter to the direction of movement of books along the second path.

The method may further comprise the steps of inspecting each book immediately prior to entry into the second path, and such inspecting step may comprise determining whether or not the end papers which flank the leaves adhere to the respective covers and introducing into the second path only those books wherein the end papers do not adhere to the covers.

The first moving step preferably includes maintaining the panels of successive jackets in a substantially horizontal plane during travel along the first path, and the second moving step preferably comprises maintaining the covers of successive books in a substantially horizontal plane during travel along the second path.

The method may further comprise the step of moving jacketed books along a third path, and such step preferably includes maintaining the jacketed books in a substantially vertical plane, at least during the interval immediately following the removal from the assembly station.

The step of converting blanks into jackets preferably comprises heating the blanks in regions where the flaps adhere to the respective central panels, especially if one or both sides of each blank are coated with a film of thermoplastic synthetic plastic material. Such heating results in the formation of permanent creases in the regions where the flaps adhere to the respective central panels.

The method preferably further comprises the steps of monitoring the one and/or the other path for the presence of jackets and/or books therein, and interrupting the movement of books or jackets along the respective path in response to detected absence of jackets or books.

The flaps are preferably maintained in a predetermined orientation with respect to the corresponding central panels at the assembly station so as to insure that the covers of an opened book can find their way into the spaces between the flaps and the panel of a jacket which is to be assembled with such book.

A jacketed book is preferably moved from the assembly station to a lower level and is preferably held in a vertical plane during such movement. The movement to a lower level is preferably followed by a sidewise movement of the jacketed book or by tilting of the book into a substantially horizontal plane. The evacuation of a jacketed book from the assembly station is preferably accompanied, preceded or followed by the step of aligning the jacket with the respective book so

that the panel of the jacket fully overlaps, conceals and hence protects the respective covers. This can be achieved by causing the leading edges of the covers to abut against a suitable stop immediately upon evacuation from the assembly station or by causing the jacketed books to vibrate upon evacuation from the assembly station so as to shift the covers relative to the jacket and/or vice versa.

The novel features which are considered as characteristic of the invention are set forth in particular in the appended claims. The improved jacketing apparatus itself, however, both as to its construction and its mode of operation, together with additional features and advantages thereof, will be best understood upon perusal of the following detailed description of certain specific embodiments with reference to the accompanying drawing.

BRIEF DESCRIPTION OF THE DRAWING

FIG. 1 is a somewhat schematic plan view of a first jacketing apparatus which embodies the invention;

FIG. 1a is a perspective view showing successive stages of making a jacket and the assembly of such jacket with a book;

FIG. 2 is a schematic elevational view of the apparatus of FIG. 1;

FIG. 3 is an enlarged transverse vertical sectional view substantially as seen in the direction of arrows from the line III—III of FIG. 1;

FIG. 4 is an enlarged fragmentary longitudinal vertical sectional view as seen in the direction of arrows from the line IV—IV of FIG. 3;

FIG. 5 is an enlarged view of a detail in FIG. 3, showing one of two mobile blank folding members in an idle position;

FIG. 6 shows the structure of FIG. 5 but with the one folding member in an intermediate position;

FIG. 7 shows the structure of FIG. 5 or 6 but with the one folding member in an operative position;

FIG. 8 is an enlarged fragmentary sectional view as seen in the direction of arrows from the line VIII—VIII of FIG. 1;

FIG. 9 is an enlarged fragmentary sectional view as seen in the direction of arrows from the line IX—IX of FIG. 1;

FIG. 10 is an enlarged transverse vertical sectional view as seen in the direction of arrows from the line X—X of FIG. 1;

FIG. 11 illustrates the structure of FIG. 10 but with the closing arms for book covers in operative positions;

FIG. 12 is a fragmentary longitudinal vertical sectional view as seen in the direction of arrows from the line XII—XII of FIG. 10;

FIG. 13 is a plan view of a control panel in the apparatus of FIGS. 1 to 12;

FIGS. 14, 15, 16, 17 and 18 illustrate the details of the control circuit in the apparatus of FIGS. 1 to 12;

FIG. 19 is a perspective view of a portion of a second apparatus;

FIG. 20 is an end elevational view of a vibrating trough in the apparatus of FIG. 19; and

FIG. 21 is a perspective view of a portion of a third apparatus.

DESCRIPTION OF THE PREFERRED EMBODIMENTS

FIGS. 1 and 2 show a first jacketing apparatus which comprises several units serving to manipulate suc-

sive jackets 15 and books 25 in a manner which will be briefly outlined by referring simultaneously to FIG. 1A. The jackets 15 are obtained in response to deformation of rectangular blanks or sheets 16 consisting of paper or other suitable material. The blanks 16 form a stack 17 (FIG. 2) which is supported by a platform 35 of the jacketing apparatus. The platform 35 is mounted at one end of a frame 36 and is movable up and down.

The first step in deforming a blank 16 includes providing it with two flaps 18, 19 which partially overlap one side of the central portion or panel 20 of the respective blank. The panel 20 remains flat or substantially flat while the thus obtained jacket 15 moves edge-wise toward the other end of the frame 36 so as to be automatically assembled with a book 25 which, at that time, is moved in a direction toward the stack 17 with its covers 26, 27 located in a common plane and with its leaves or sheets 24 located in planes which are normal or substantially normal to the common plane of the covers 26, 27. As a freshly formed jacket 15 advances in the direction indicated by an arrow 37, the corresponding book 25 advances in the direction indicated by an arrow 137 whereby the outer portions of the covers 26, 27 automatically enter the spaces between the flaps 18, 19 and the central panel 20 before the apparatus begins to pivot the covers toward each other so that the flaps are ultimately confined between the covers and the respective free end papers 28, 29. The closed book 25, with the jacket 15 thereon, is thereupon caused to move downwardly by sliding along an inclined chute 38 whereby the front edges of its covers strike against a stop 39 which shifts the jacket 15 (if necessary) so that the front edge of the jacket is flush with the adjacent edges of the covers. The properly jacketed books is then ready for manual or automatic transfer into storage or into a receptacle, e.g., into a crate, box or the like.

The books 25 are inspected before they reach the upper stretch of a first belt conveyor 40 which travels below two upright inner guides 41, 42 for the sheets 24 and free end papers 28, 29. When the sheets 24 and end papers 28, 29 enter the gap between the inner guides 41, 42, the covers 26, 27 (which lie flat on the upper stretch of the belt conveyor 40) travel below the guides 41, 42 and between two outer guides 43, 44 which are adjustable along a transversely extending horizontal rod or bar 45 so that the width of the space between the guides 43, 44 slightly exceeds the width of an open book 25. The inner guides 41, 42 are adjustable along a similar transversely extending rod or bar 46. The inner guides 41, 42 respectively carry idler rollers or wheels 47, 48 which roll along the inner sides of open covers 26, 27 while a book 25 advances with the conveyor 40 and onto the upper stretch of a shorter second belt conveyor 49. The conveyors 40, 49 are driven by a motor 50 in such a way that the conveyor 49 travels faster in order to automatically increase the distance between a preceding book 25 and the next-following book.

The motor 50 is preferably of the variable speed type so that it can change the speed of the conveyors 40 and 49, if and when necessary, particularly when the jackets 15 on the books 25 abutting the stop 39 of FIG. 2 are not in accurate register with the respective covers 26, 27. The speed of the conveyor 40 changes proportionally with that of the conveyor 49 in response to each change or RPM of the motor 50.

A book 24 which is placed onto the conveyor 40 has been inspected by an attendant who determines whether or not the end papers 28, 29 adhere to the covers 26, 27. Such inspection is desirable in order to insure that a jacket 15 is not destroyed or damaged during attachment to a defective book. If the book is satisfactory, its sheets 24 and end papers 28, 29 are introduced into the vertical gap between the inner guides 41, 42 whereby the belt conveyor 40 entrains the covers 26, 27 and advances the book onto the belt conveyor 49. The attendant can separate the end papers 28, 29 from the respective covers 26, 27 if the bond between the end paper 28 or 29 and the respective cover 26 or 27 can be destroyed without affecting the appearance and/or integrity of end papers and/or covers.

A blank 16 which has been removed from the stack 17 on the mobile platform 35 by one or more suction cups is deposited on the downwardly inclined upper stretch of a belt conveyor 51 so that the blank can advance toward a folding station 52. The platform 35 can descend automatically in response to removal of discrete blanks 16 or upon completed removal of several (e.g., five, six, seven or eight) blanks, depending on the thickness of blanks. All that counts is to insure that the uppermost blank 16 of the stack 17 can be reached by the suction cup or cups for transfer onto the belt conveyor 51. The means for lifting the platform 35 in step-wise fashion may comprise an intermittently rotated feed screw 35a or any other suitable lifting means.

A blank 16 which reaches the folding station 52 is treated as follows: Such blank rests on two timing belt conveyors 53 (FIGS. 2 and 3) which are advanced step-wise to move the jackets 15 toward a station 54 where the jackets are assembled with the books 25. The conveyors 53 have aligned entraining elements 53a which locate successive blanks 16 in predetermined positions at the folding station 52 so that a blank at the station 52 is in an optimum position for the making of flaps 18, 19, i.e., for conversion into a jacket 15.

The folding instrumentalities at the station 52 include two blank guides 55, 56 (FIG. 3) which center the blanks 16 at the station 52, two fixed folding or creasing members 57, 58 above the upper stretches of the timing belts 53 and two mobile folding or creasing members 59, 60 which are respectively disposed between the guides 55, 56 and folding members 57, 58 and are movable between the positions shown for the folding member 60 in FIGS. 5, 6 and 7. The folding instrumentalities further comprise two pressure plates 61, 62 which can be biased upwardly by springs 63 to urge the blank 16 against the respective fixed folding members 57, 58 during the making of flaps 16, 17. The means for moving the folding member 60 and the associated pressure plate 62 comprises a sleeve 64 (FIGS. 5-7) which surrounds a rod-like support 65 for the pressure plate 62, a piston rod 66 which carries the sleeve 64 and axially movably supports the support 65, a first link 67 which is articulately connected to the sleeve 64 and carries the folding member 60, and a second link 68 which is articulately connected with the link 67 and receives motion from a piston rod 69. The piston rods 66 and 69 are respectively movable by pneumatic cylinders 66a and 69a (FIG. 3) whose operation is synchronized so that the folding member 60 can be moved from the inoperative or retracted position of FIG. 5, through the intermediate position of FIG. 6, and to the operative position of FIG. 7 to thereby provide a blank 16 with the flap 19. The mem-

ber 60 is thereupon retracted to the position of FIG. 5 before the jacket 15 is advanced toward the assembly station 54. The operation of the folding member 59 and pressure plate 61 is analogous (see the cylinders 66b and 69b).

Each of the folding members 59, 60 has a groove 70 which receives the outermost portion of the associated folding member 57, 58 during creasing of a blank 16. The folding members 57, 58 are heated by heating units 10 HE₁ and HE₂ to thereby promote the formation of permanent creases between the central panel 20 and the flaps 18, 19, especially if the material of blanks 16 include layers of synthetic thermoplastic material.

It is clear that the heating units HE₁ and HE₂ (or analogous heating units) can be provided on or associated with the mobile folding members 59, 60. Furthermore, the apparatus may comprise a heating unit for each of the folding members 57-60. The arrangement of FIG. 3 is preferred at this time because the heating units HE₁ and HE₂ remain stationary.

Freshly formed flaps 18, 19 are thereupon caused to pass through a channel 73 (FIG. 8) which terminates short of the assembly station 54 so that the flaps 18, 19 are free to pivot to the positions shown for the flap 19 in FIG. 9. In such positions, the flaps are sufficiently spaced from the central panel 20 of a jacket 15 to allow for introduction of the respective covers 26, 27 at the station 54. The belt conveyors 51 and 53 are driven by a main motor 74 through the medium of a clutch 75 shown in FIG. 2.

The assembling of books 25 with jackets 15 takes place on a platform 76 (FIGS. 2 and 12) which is pivotable at 77 to permit a jacketed book to descend into the chute 38. The means for assembling includes two closing arms 78, 79 (FIGS. 10 and 11) having portions 78a, 79a which overlie the flaps 18, 19. The arms 78 and 79 are pivotable at 80, 81 to move the covers 26, 27 from the open positions of FIG. 10 to the partly closed positions of FIG. 11. The means for pivoting the arms 78, 79 comprises links 82, 83 which are attached to a cross-head 84 on the piston rod 85 of a pneumatic cylinder 86 in the frame 36.

The portions 78a, 79a of the closing arms 78, 79 have roller followers 78b, 79b which engage stationary cams 45 87, 88 when the arms 78, 79 assume the idle positions shown in FIG. 10. The extensions 78c, 79c of the portions 78a, 79a are then spaced apart from the adjacent flaps 18, 19 of a jacket 15 at the assembly station 54. Springs 89, 90 respectively bias the portions 78a, 79a in directions indicated by arrows 91, 92 so as to move the extensions 78c, 79c flush against the flaps 18, 19 (FIG. 11) when the roller followers 78b, 79b are disengaged from the cams 87, 88. The portions 78a, 79a are adjustable with respect to the main portions of the respective arms 78, 79 so that these arms can be used for the closing of covers of smaller or larger books. As shown in the right-hand portion of FIG. 10, the main portion of the closing arm 78 has several tapped bores 93 for screws or analogous fasteners 94 which can secure the portion 78a in a desired position at a selected distance from the pivot 80. The adjustable mounting of portion 79a on the main portion of the closing arm 79 is analogous.

The platform 76 is pivotable by the piston rod 95 of a pneumatic cylinder 96 shown in FIG. 12.

The free end papers 28, 29 of the books 25 are inspected on a table or platform 97 (FIG. 2) whose upper side is flush with the upper stretch of the belt conveyor

40.

A book at the assembly station 54 overlies the platform 76 to such an extent that it slides off the latter as soon as the platform is pivoted to its inclined position.

A jacketed book 25 which abuts against the stop 39 of FIG. 2 is moved sideways by an intermittently operated piston rod (see the piston rod 204 of FIG. 19) to provide room for the next-following book. The books which are pushed aside by the piston rod form a row of books in a channel which can discharge books onto a take-off conveyor or from which the books are removed at intervals by an attendant who places stacks of uninspected books onto the table 97. The piston rod which expels jacketed books from the chute 38 forms part of a double-acting pneumatic cylinder and piston unit DP5. The unit DP5 can be replaced by an electromagnet or by any other suitable means for expelling a jacketed book which abuts against the stop 39.

It is also within the purview of the invention to move jacketed books alternately to opposite sides of the stop 39, i.e., to provide a channel at each side of the chute 38. The unit DP5 is then replaced with an evacuating unit which can move jacketed books which abut the stop 39 toward or away from the observer of FIG. 2.

The frame 36 further supports a control panel 105 for signal lamps, actuating knobs, gauges and other elements of the control system, see FIG. 13. The parts on the top face of the control panel 105 include a selector knob for a switch MS2 which can be moved between a first position (MANUAL), a second position (OFF) and a third position (AUTOMATIC). Two lamps are provided to indicate that the heaters HE₁ and HE₂ for the fixed folding members 57, 58 are on or off. Another knob is provided for a main switch MS1. The other pushbuttons on the control panel 105 serve to actuate switches PB3-PB10 and PB13-PB16. Two additional knobs on the panel 105 serve to select the positions of moving contacts of switches MS4 and MS5.

FIGS. 14 to 18 show a circuit diagram of a control arrangement in the apparatus of FIGS. 1-13. The components of this circuit are as follows:

Units R1, R5, R7, R8 and R15 are eleven-terminal relay devices, the terminals of each such relay device being designated 1, 2, 3, 4, 5, 6, 7, 8, 9, 10, 11. Each of these relay devices comprises a relay winding (connected between the respective terminals 2 and 10) and three normally closed relay switches which are respectively connected between terminals 1 and 4, 5 and 6, and 11 and 8. When a relay winding between the terminals 2 and 10 becomes energized, it causes the associated relay switches to open. Each of the relay devices R1, R5, R7, R8 and R15 further comprises three normally open relay switches which are respectively connected between terminals 1 and 3, 6 and 7, and 11 and 9. When the relay winding between the terminals 2 and 10 of a relay device becomes energized, it causes the associated normally open relay switches to close.

The units R2, R3, R4, R6, R10 and R16 are eight-terminal relay devices, the terminals of each such relay device being designated 1, 2, 3, 4, 5, 6, 7, 8. Each of the eight-terminal relay devices comprises a relay winding (connected between the respective terminals 2 and 7) and two normally closed relay switches respectively connected between terminals 1 and 4, and between terminals 8 and 5. When a relay winding between the terminals 2 and 7 becomes energized, it causes the associated normally closed relay switches to open. Each of the relay devices R2, R3, R4, R6, R10 and R16 further

comprises two normally open relay switches which are respectively connected between terminals 1 and 3, and between terminals 8 and 6. When a relay winding between the terminals 2 and 7 becomes energized, it causes the associated normally open relay switches to close.

The units R12, R13 and R33 are eight-terminal relay devices which are identical to the relay devices R2, R3, R4, R6, R10 and R16. However, all eight terminals of the relay devices R12, R13 and R33 are not shown in the drawing; only the terminals 2 and 7, between which is connected the respective relay winding, are explicitly marked. It will be understood, however, that the other terminals and interconnecting switches are nonetheless present.

The units R9 and R11 are eight-terminal time-delay relay devices, in all respects identical to the eight-terminal relay devices just described, except that the relay switches of the relay devices R9 and R11 do not respond immediately to the establishment of energizing current in the respective relay winding; they respond only after the elapse of a predetermined adjustable time delay interval.

The unit R14 is an eleven-terminal latching relay device having terminals designated A, B, 1, 2, 3, 4, 5, 6, 7, 8, 9 (terminals 2 and 5 not shown). The device R14 comprises two normally closed relay switches which are respectively connected between the terminals 1 and 7, and between the terminals 3 and 9; two normally open relay switches which are respectively connected between terminals 4 and 7, and between terminals 6 and 9; and a bistable relay coil arrangement, not shown. Terminal B serves as SET input, whereas terminal 8 serves as a RESET input. When a SET pulse is applied to the terminal B, the two normally closed and the two normally open relay switches of the device R14 respectively assume their open and closed positions. Conversely, when a RESET pulse is applied to terminal 8, the four relay switches in R14 reassume their normal positions. The terminal A is a supply terminal which is directly connected to a voltage supply line AT29.

The various terminals of the relay devices R1 through R16 are interconnected with each other. In order to facilitate understanding, where appropriate, each such terminal of each of the relay devices R1 through R16 which is connected to a terminal of another relay device is labelled to designate the other terminal. For example, the terminal 3 of relay device R3 is designated with the legend "R4T2", signifying that this terminal is connected to the terminal 2 of relay device R4; conversely, the terminal 2 of relay device R4 is designated with the legend "R3T3", symbolizing the just-explained fact that the terminal 2 of R4 is connected to terminal 3 or R3.

The circuit of FIGS. 14-18 includes connections between the terminals of different relay devices R1 through R16, connections between terminals belonging to the same relay device, and also connections from such terminals to other components of the control circuit. For example, the terminal 1 of the relay device R5 is connected directly to terminal 2 of R5; this connection is readily perceivable because it involves two terminals of the same relay device so that no explanatory legend is necessary. See also the readily traceable direct connection between the terminal 2 of R7 and the terminal 2 of R8. The terminal 9 of R7 is connected to a remote circuit junction AT1; this explains the use of the legend "AT1" at terminal 9 of R7. The application

of such legend eliminates the need for showing a long connecting wire which would be difficult to trace. The connections between certain relay switches which are installed in the relay devices R1 to R16 are shown as being connected external to the respective relay devices. For example, FIG. 16 shows a normally closed switch beneath which appears the legend "R3" indicating that this normally closed switch is one of the normally closed relay switches in the relay device R3; furthermore, the left-hand and right-hand terminals of this switch are designated 8 and 5, respectively, indicating that the switch in question is the normally closed switch between the similarly numbered terminals of the relay device R3. Immediately to the right of the switch above the reference character R3 in FIG. 16, there is shown a further switch above the legend "R4" which indicates that this is one of the switches in the relay device R4; furthermore, the terminals of this switch are shown at 8 and 6, signifying that the switch in question is installed in and connected between the similarly designated terminals of the relay device R4. The two switches just discussed are shown as being connected with each other in series, and this is consistent with the use of symbolic legends at the terminals of the relay devices R1 through R16. For example, still referring to the switches R3(8-5) and R4(8-6) of FIG. 16, it will be seen that the terminal 5 of switch R3(8-5) is connected directly to terminal 8 of switch R4(8-6). Looking at the relay device R3 in FIG. 16, it will be noted that the terminal 5 is labelled "R4T8", signifying that such terminal is directly connected to terminal 8 of the relay device R4; conversely, the terminal 8 of relay device R4 in FIG. 16 is labelled "R3T5", signifying that this terminal is connected directly to terminal 5 of the relay device R3.

It will be noted that the connections are shown symbolically by means of legends and, additionally, by showing the internal relay switches connected to each other as though they were external to the respective relay devices.

The motor 1M of FIGS. 15 and 16 is the book infeed motor 50 shown in FIG. 2. This motor is depicted twice in order to reduce the number of lines representing conductor wires.

The motor DM of FIG. 15 is the main motor 74 which drives the timing belts 53 of FIGS. 2-3 through the intermediary of clutch 75.

The motor TM of FIG. 15 is the motor (not depicted in FIG. 2) which raises and lowers the stack-supporting platform 35 of FIG. 2 by rotating the feed screw 35a.

The motor V1M of FIG. 15 drives a fan or another suitable suction generating device for the (non-illustrated) suction cups which, in FIG. 2, transfer successive blanks 16 from the stack 17 onto the belt conveyor 51.

The motor V2M (shown also in FIG. 2) drives a fan or the like to generate suction for a suction holding device which holds a jacket 15 in place at the assembly station 54. In FIG. 2, there is shown a pneumatic conduit 120 leading from motor V2M to a member 121 positioned intermediate the folding arms 78, 79 and the conveyor belt 49. The member 121 extends transversely to the direction of book advancement and serves to hold the jacket 15 in place by applying suction substantially across the entire transverse width of the jacket at station 54.

The motors DM, TM, V1M, V2M and 1M are driven by three-phase current. The three-phase power lines are designated L1, L2, L3.

FIG. 14 shows the main switch MS1 which must be closed if the motors DM, TM, V1M, V2M and 1M are to be driven. However, the closing of main switch MS1 is not sufficient to cause these motors to run. Each of these motors is connected to the supply lines L1, L2, L3 by one or more trios of relay switches.

Motor DM is connected to power lines L1, L2, L3 by way of a trio of relay switches designated D (FIG. 15). These relay switches close when a relay winding RD (FIG. 14) is energized.

Motor TM is connected to power lines L1, L2, L3 by way of a first trio of relay switches designated R17' and by way of a second trio of relay switches designated R12' (FIG. 15). When one of these trios of relay switches closes, the motor TM turns in a first direction, causing the platform 35 (FIG. 2) to rise; when the other of these trios of relay switches closes, the motor TM turns in the opposite direction, causing the platform 35 to descend. Relay switches R12' close when the winding of relay device R12 is energized; likewise, relay switches R17' close when a relay winding R17 (FIG. 14) is energized.

Additionally, motor TM is connected to the power lines L1, L2, L3 by a further trio of relay switches designated T. These relay switches close when an associated (non-illustrated) relay winding becomes energized. This (non-illustrated) winding becomes energized whenever the main switch MS1 is closed.

Motors V1M and V2M are both connected to power lines L1, L2, L3 via a trio of relay switches designated V (FIG. 15). Switches V close when a relay winding RV (FIG. 14) is energized.

Motor 1M (designated 50 in FIG. 2) has two terminals 6, 6. The right-hand terminal 6 is connected to power line L3 through the intermediary of one of two relay switches R2'; the left-hand terminal 6 is connected to power line L1 through the intermediary of the other relay switch R2' and a relay switch 1M' which is in series with the other relay switch R2'. The relay switches R2' close when the winding of the relay device R2 is energized. The trio of relay switches designated H2, 1M', H1 closes when the main switch MS1 is closed because a (non-illustrated) relay winding associated with this trio of switches becomes energized when MS1 is closed.

The first heater element HE1 is connected between two terminals H1' shown in FIG. 15. The right-hand terminal H1' is connected to power line L3 by way of two right-hand relay switches R21'. The left-hand terminal H1' is connected to power line L2 by way of two left-hand relay switches R21', and further by way of the relay switch H1 which, as stated above, closes when the main switch MS1 is closed. Relay switches R21' close when relay winding R21 (FIG. 15) is energized.

The second heater element HE2 is connected between two terminals H2' shown in FIG. 15. The manner in which this second heating element is connected to power by way of relay switches R22' is analogous to that just explained with respect to the first heating element, but the second heating element is under the control of a further relay winding R22 shown in FIG. 15.

The two relay windings R21, R22, which control the energization of the heater elements HE₁ and HE₂, are in turn controlled by adjustable thermostat heater control units HC1 and HC2. Each of the two heater control units HC1, HC2 may for example essentially comprise a bimetallic switch located in heat-exchanging relationship with the respective heater element. Each of the

thermostat heater control units HC1 and HC2 further comprises conventional adjusting means for selecting the temperature at which the respective bimetallic switch element opens. Accordingly, each of the adjustable units HC1, HC2 is set to a temperature at which the respective heater element is to be maintained.

FIG. 14 shows a step-down transformer. The 220V primary has a first terminal connected directly to power line L3 and a second terminal connected to power line L1 by way of four series-connected normally closed heat-responsive switches designated, in order, D', T', V', H2"-1M"-H1". These heat-responsive switches are associated with relays bearing the same designations (only the relays RD and RV shown). If any one of such relays overheats, the associated normally-closed heat-responsive switch opens, thereby disconnecting the transformer primary from power. The 110V secondary of the transformer is connected across terminals AT29, AT32 and furnishes A.C. voltage for the various relay windings of the circuit.

The control circuit additionally includes an electromagnetically activatable "one-revolution clutch" the electrical part of which is designated CL. The mechanical part of this clutch is shown diagrammatically in FIG. 2 at 75. When the electrical part CL of the clutch is energized, the clutch establishes a torque-transmitting connection between the output shaft of the main motor DM (shown at 74 in FIG. 2) and the shaft which drives the belt conveyors 51, 53 for the blanks and jackets. Specifically, the "one-revolution clutch" CL, 75 establishes such engagement when CL becomes energized. Once engaged, the clutch remains engaged until the main drive shaft for the belt conveyors 51, 53 has performed exactly one revolution; upon completion of such one revolution, the clutch disengages by purely mechanical means. In other words, only the engaging of clutch is electrically controlled, the disengaging of the clutch is effected automatically by mechanical means.

The control circuit further includes a cam motor designated CM. The output shaft of cam motor CM is provided with cam means which control four cam switches CS1, CS2, CS3, CS4. These switches open and close when the cam motor CM assumes various predetermined angular positions.

The control circuit further includes two photoelectric monitoring units EE1 and EE2. Each of the units EE1, EE2 has terminals designated 1, 2, 3, 4, 5, 6, 7, 8, 9. The terminals 8 and 9 are connected to power lines L1, L2, respectively, from which is derived the operating power for the monitoring units. Connected between terminals 1 and 2 of each of the units EE1, EE2 is a photosensitive element arranged in the path of a non-illustrated light source.

The photosensitive element of EE1 is positioned two thirds down the inclined chute 38. When no book blocks the light path of the photosensitive element, the normally closed switch between terminals 6 and 7 of EE1 remains closed, and the indicator lamp connected between terminals 3 and 4 of EE1 is not illuminated. When the light path of the photosensitive element is blocked, the normally closed switch between terminals 6 and 7 of EE1 opens, and the indicator lamp connected between terminals 3 and 4 of EE1 lights up. The internal circuitry of the monitoring unit EE1 is conventional.

The photosensitive element of the monitoring unit EE2 is positioned at the jacket forming station 52.

When the light path of the photoelement of unit EE2 is blocked by a jacket at the folding station 52, the normally open switch connected between terminals 5 and 7 of EE2 closes, and the indicator lamp connected between terminals 3 and 4 of EE2 lights up. When no jacket is present at the folding station 52, the switch connected between terminals 5 and 7 of EE2 opens, and the indicator lamp connected between terminals 3 and 4 of EE2 is off.

LS1 is a limit switch mounted on one of the guides 41, 44 (see FIG. 1). The location of limit switch LS1, relative to the belt conveyors 40, 49, is shown in FIG. 2. When a book is fed from the slower conveyor 40 onto the faster conveyor 49, the limit switch LS1 closes. The closing of limit switch LS1 by a book reaching the conveyor 49 initiates a jacketing cycle.

LS2 is a limit switch located downstream of the limit switch LS1, the spatial relationship being shown in FIG. 2. LS2 is closed when engaged by the leading end of an advancing book and opens when the trailing end of such book advances beyond its movable portion.

LS3 is a limit switch located at the end of the inclined chute 38 shown in FIG. 2; this switch closes when a jacketed book reaches the stop 39.

LS4 is a limit switch shown also in FIGS. 2, 10 and 11. This switch is closed by the crosshead 84 when the latter rises from the position shown in FIG. 10 to the position of FIG. 11. Thus, the switch LS4 closes in response to folding of the covers 26, 27 against the free end pages 28, 29 at the assembly station 54.

LS5 is a normally closed limit switch which cooperates with a pneumatic book-removing arrangement including the double-acting cylinder and piston unit DP5 shown in FIG. 2. When a jacketed book reaches the bottom of the chute 38 and closes the limit switch LS3, the piston rod of the unit DP5 performs a working stroke and expels the jacketed book from the chute by moving the book in a direction normal to the plane of FIG. 2. When the piston of DP5 reaches the end of such working stroke, it opens the limit switch LS5 which thereby indicates that the chute 38 is empty.

LS6 and LS7 are cam-controlled switches. As explained above, when the electrical part CL of the one-revolution clutch CL, 75 is energized, a drive shaft

45 which drives the conveyors 51, 53 is caused to complete a single revolution. This one-revolution drive shaft is provided with non-illustrated cam means which control the switches LS6 and LS7. These switches remain closed while the one-revolution drive shaft moves from the 0° position to the 330° position; the switches LS6 and LS7 are open while the one-revolution drive shaft moves from the 330° position to the 360° position.

LS8 and LS9 are normally closed limit switches which are actuated by the stack supporting platform 35

55 of FIG. 2 and respectively determine the lowermost and uppermost permissible positions for the platform. If it is desired to cause the platform 35 to rise, the movable contact of a switch MS5 shown in FIG. 14 is moved from the illustrated neutral position to its lower

60 position, thereby completing the current path for relay winding R12. Energization of relay winding R12 results in closing of the trio of associated relay switches R12' so that the motor TM becomes connected to power and turns in a direction to cause the platform 35 to rise.

65 When the platform 35 has risen to the maximum permissible level, it opens the limit switch LS9 which interrupts the current path of relay winding R12, thereby opening the trio of relay switches R12 and thereby

causing the platform-controlling motor TM to become disconnected from power.

If it is desired to cause the platform 35 to descend, the movable contact of the switch MS5 is moved from its neutral position to its upper position to complete the current path of relay winding R17. The energization of relay winding R17 causes the associated trio of relay switches R17' to close, thereby causing motor TM to turn in a direction causing the platform 35 to descend. When the platform 35 has descended to the lowest permissible level, it engages the limit switch LS8 which opens and interrupts the current path of relay winding R17, thereby opening the trio of relay switches R17'.

When the control circuit is to be set for automatic operation, the movable contact of the switch MS5 is placed into its lowermost position, i.e., the "UP" position for the stack-supporting platform 35 of FIG. 2.

LS10 is a limit switch composed of two mechanically connected moving switch members, as shown in FIG. 14. This relay is activated by the top of the stack of blanks 16 supported on the platform 35 of FIG. 2. When the top of the stack of blanks rises to a predetermined level (the movable contact of switch MS5 is in the platform "UP" position), the uppermost blank of the stack activates the switch LS10 which energizes the relay winding R13 and deenergizes the relay winding R12 to terminate the upward movement of the stack-supporting platform 35. However, as successive blanks are removed from the stack and converted into book jackets, the upper level of the stack 16 will evidently descend, eventually becoming so low that the limit switch LS10 reassumes its illustrated position. As a result, the relay winding R12 will become energized again, and the motor TM will cause the platform 35 to rise until the topmost blank of the stack 16 again reaches and actuates the limit switch LS10.

The four cam-controlled switches CS1, CS2, CS3 and CS4 open and close when the output element of the cam motor CM assumes various predetermined angular positions.

CS1 is open while the output element of the cam motor CM is between the 0° and 30° positions and is closed while the output element between the 30° and 360° positions.

CS2 is open while the output element of the cam motor CM is between the 0° and 40° positions, and is closed while the output element is between the 40° and 330° positions.

CS3 is open while the output element of the cam motor CM is between the 0° and 60° positions, is closed while the output element is between the 60° and 300° positions, and is open again while the output element is between the 300° and 360° positions.

CS4 is open while the output element of the cam motor CM is between the 0° and 20° positions, is closed while the output element is between the 20° and 330° positions, and is again open while the output element is between the 330° and 360° positions.

The control circuit further includes five solenoids AC1 through AC5 which are shown in FIGS. 16 and 17. Each of the solenoids AC1 through AC5 is installed in the housing of one of the similarly referenced three-port two-position pneumatic switchover valves AC1 through AC5 shown in FIG. 2. The solenoids AC1 to AC5 are the control solenoids of the respective pneumatic switchover valves. For any one of the five switchover valves, when the respective control solenoid is energized, the associated valve member moves to estab-

lish communication between the valve inlet and one of the two valve outlets; when the control solenoid is de-energized, communication is established between the valve inlet and the other of the two valve outlets. The control solenoid AC6 (FIG. 18) is not used.

Associated with the pneumatic switchover valves AC1 to AC5 of FIG. 2 are double-acting cylinder and piston units DP1 to DP5. Each of the units DP1 to DP5 has a first port connected to one of the outlets of the respective switch-over valve and a second port connected to the other outlet of the respective switch-over valve. Compressed air is applied to the inlets of all of the switchover valves AC1 to AC5 of FIG. 2, the air being routed to one or the other of the two ports of the associated cylinder and piston unit, depending upon whether the respective control solenoid is energized or not.

The double-acting cylinder and piston unit DP1 includes the cylinder 86 and piston rod 85 (see FIGS. 10 and 11). When the piston of the unit DP1 is in one of the two positions thereof, the arms 78, 79 occupy the positions shown in FIG. 10. When the piston of the unit DP1 is in the other position, the arms 78, 79 occupy the positions shown in FIG. 11.

The unit DP2 includes the cylinder 96 and piston rod 95 (see FIG. 12). When the piston of the unit DP2 is in one of its two positions, the pivotable platform 76 (FIG. 12) is in the horizontal position thereof. When the piston of the units DP2 is in the other position, the platform 76 is tilted so as to cause a jacketed book thereon to drop down into the chute 38.

The apparatus comprises two substantially identical units DP3 each of which includes a piston rod 66 and one of the cylinders 66a, 66b. One of the units DP3 controls the upward and downward movements of pressure plate 61 (see FIG. 3), while the other of the units DP3 controls the upward and downward movements of the pressure plate 62. The pressure plate 62 is shown in its lower position in FIG. 5, and in its upper position in FIG. 6.

Each of the two substantially identical double-acting cylinder and piston units DP4 comprises a piston rod 69 (FIG. 3) and one of the cylinders 69a, 69b. Each piston rod 69 controls, in conjunction with the corresponding piston rod 66, the position of the respective folding member 59 or 60 (FIG. 3).

The function of the unit DP5 has been described above.

MS2 (shown in FIG. 14) is an auto/manual mode selecting switch, and MS3 (FIG. 14) is an emergency switch. When MS3 is closed, the relay winding of relay device R33 becomes energized, thereby opening the relay switches R33(1-4) and R33(8-5) (FIG. 14) to thus disconnect the 110V secondary of the transformer from the various A.C. relays. All motors stop.

MS4 (FIG. 15) is a heater control switch. The heating elements HE₁ and HE₂ connected between terminals H1', H1' and H2', H2' become energized when switch MS4 is closed.

Finally, the control circuit includes thirteen pushbutton-activated switches PB3 to PB11 and PB13 to PB16. These switches are shown in FIGS. 14 and 16-17.

The switches PB3 to PB11 are employed only in the manual operating mode, for machine set-up and check-out procedures. They activate individual components of the machine.

When briefly closed, the switch PB13 energizes the relay winding of relay device RD, thereby causing the

trio of associated relay switches D to close and to start the main drive motor DM. In addition, when relay device RD is on, the relay switch D (FIG. 14) connected in parallel with pushbutton-activated switch PB13 closes, thereby establishing a self-locking action which maintains RD on even after PB13 opens upon release of the associated pushbutton.

When pushed open, the switch PB14 interrupts the current path of the relay winding of RD to terminate the self-locking action and to arrest the main drive motor DM.

When briefly closed, the switch PB15 establishes a current path for the relay winding of relay device RV. Accordingly, the trio of relay switches V closes to start the vacuum motors V1M and V2M. Also, the relay switch V (FIG. 14) connected between terminals AT30 and AT25 closes to establish a self-locking action which maintains the relay winding of RV energized even after the switch PB15 opens upon release of the associated pushbutton.

When actuated, the switch PB16 interrupts the current path for the relay winding of relay device RV to terminate the self-locking action and to stop the vacuum motors V1M and V2M.

To set the control circuit of FIGS. 14 to 18 for "automatic" mode of operation, the operator proceeds as follows: The main switch MS1 is closed. The pushbuttons associated with switches PB13 and PB15 are briefly depressed to start the main drive motor DM and the vacuum motors V1M and V2M. The heater control switch MS4 is closed, so as to permit energization of the heater elements HE₁ and HE₂. The switch MS2 is moved to the "AUTO" position and the movable contact of switch MS5 is moved to its lower position. Finally, the pushbutton associated with switch PB11 is depressed and held depressed until a blank is advanced to the folding station 52 and converted into a jacket. In the "automatic" mode, switch PB11 is connected in parallel with the limit switch LS3. The manner in which pushbutton-activated switch PB11 performs the just mentioned function will become clear from the detailed description of the operation of limit switch LS3 during "automatic" operation of the circuit. In the "automatic mode" the relay devices R7, R8 and R10 never go on. This is because the switch MS2 is in series with the pushbutton-activated switch PB8 which is open. Accordingly, the voltage supply line AT27 for the relay devices R7, R8 and R10 is disconnected from power.

The operation of the control circuit in the "automatic" mode is as follows:

1. An attendant inspects a book on the table 97 of FIG. 2 and feeds a satisfactory book onto the first belt conveyor 40.

2. The book 25 enters the space between the guides 41, 42 to trip the limit switch unit LS1 which assumes a position other than that shown in FIG. 16. Such tripping of the limit switch LS1 constitutes the beginning of a machine operating cycle.

3. As a result of tripping of limit switch LS1, a SET pulse is applied via closed switch R15(11-8) to the SET input B of the bistable relay device R14 so that the relay device R14 undergoes a transition into the ON state thereof.

4. Since the relay device R14 is on, the switch R14(7-4) shown in FIG. 17 closes, thereby energizing the winding of relay device R15.

5. As a result of energization of the winding of relay device R15, the switch R15(11-8) shown in FIG. 16

opens, temporarily preventing further application of SET pulses to the input B of R14.

6. The trailing end of the book 25 now advances beyond and enables LS1 to return to its illustrated position.

7. Meanwhile, however, the front portion of the book 25 has closed the limit switch LS2.

8. The closed switch LS2 energizes the winding of the relay device R3.

9. As a result of energization of the winding of R3, the switch R3(1-3) shown in FIG. 16 closes and energizes the winding of the relay device R4.

10. The book 25 advances further and allows the limit switch LS2 to open.

11. The reopening of switch LS2 results in deenergization of the winding of relay device R3.

12. However, the winding of relay device R4 remains energized because of the locking action afforded by the monitoring unit EE1. The photosensitive element of the unit EE1 is positioned two-thirds down the inclined chute 38. So long as no book blocks the light path of the photosensitive element of unit EE1, the switch connecting the terminals 6 and 7 of the unit EE1 remains closed. During the time period that the light path of the photosensitive element is blocked, the associated switch is open. Thus, once the winding of R4 becomes energized, it is held energized by the switch of the unit EE1 so that the current flows through the switch of EE1 and into the terminal 3 of R4, out from the terminal 1 of R4, and then back to the terminal 2 of R4, namely into the relay winding of R4.

13. As a result of energization of the winding of R4, current flows through solenoid AC1, via closed relay switches R3(8-5), R4(8-6) and R7(5-6). It will be recalled that the winding of relay device R7 is not energized during automatic operation of the jacketing apparatus.

14. Energization of the solenoid AC1 causes the respective pneumatic switchover valve AC1 (FIG. 2) to activate the double-acting cylinder and piston unit DP1. As a result, the piston rod 85 (FIGS. 10, 11) pushes the crosshead 84 upwards so that the closing arms 78, 79 move to the positions shown in FIG. 11 and cause the jacketed covers 26, 27 of the book 25 to close.

15. Simultaneously with the energization of solenoid AC1 through closed switches R3(8-5), R4(8-6) and R7(5-6), a RESET pulse is applied, via switches R3(8-5) and R4(8-6) to the RESET input 8 of the bistable relay device R14. Accordingly, the relay device R14 goes off.

16. The upward movement of crosshead 84 results in closing of the limit switch LS4 (see FIG. 11).

17. When the switch LS4 closes, the solenoid AC2 becomes energized.

18. As a result, the pneumatic switchover valve AC2 (FIG. 2) actuates the double-acting cylinder and piston unit DP2 (95, 96 in FIG. 12). The piston rod 95 moves downwardly and tilts the platform 76.

19. The tilting of platform 76 causes the closed jacketed book supported thereon to drop into the chute 38 (FIG. 2).

20. The book, in dropping to the bottom of chute 38, passes the photosensitive element of the monitoring unit EE1. During blocking of the light path of the photosensitive element, the normally closed switch connected between terminals 6 and 7 of the unit EE1 opens, thereby ending the locking action of relay de-

vice R4. Accordingly R4 goes off.

21. When the relay device R4 goes off, the associated relay switch R4(8-6) opens to interrupt the current path of the solenoid AC1.

22. Deenergization of the solenoid AC1 causes the pneumatic switchover valve AC1 to actuate the double-acting cylinder and piston unit DP1 which moves the closing arms 78, 79 from the positions shown in FIG. 11 back to the positions shown in FIG. 10.

23. As a result of the return movement of closing arms 78, 79 to the positions of FIG. 10, the crosshead 84 allows the limit switch LS4 to open.

24. Reopening of limit switch LS4 interrupts the current path of solenoid AC2.

25. The resulting deenergization of solenoid AC2 causes the switchover valve AC2 to actuate the double-acting cylinder and piston unit DP2 (95, 96 in FIG. 12) which moves the platform 76 back to its normal horizontal position.

26. When the book reaches the bottom of the chute 38, it contacts and closes the limit switch LS3.

27. Closing of limit switch LS3 energizes the winding of the relay device R1.

28. With R1 on, the internal connection between terminals 1 and 4 of R1 becomes interrupted, as explained with respect to the eleven-terminal relay devices. Consequently, the current path leading through limit switch LS2 is broken. Accordingly, even if limit switch LS2 should be closed and then opened as a second book moves past LS2, this will not result in energization of the control solenoid AC1 for the closing arms 78, 79 of FIGS. 10 and 11.

29. When R1 is on, its terminals 1 and 3 become internally connected to each other. Consequently, the winding of the relay device R5 is energized.

30. When R5 is on, its relay switch R5(6-7) closes to complete the current path of solenoid AC5. The relay switch R8(5-6) in series with the solenoid AC5 and the latter switch is always closed during automatic operation since the relay device R8 is off.

31. Energization of solenoid AC5 causes the switch-over valve AC5 (FIG. 2) to actuate the unit DP5 (FIG. 2) whose piston rod is or carries the book pushoff device. Consequently, the jacketed book at the bottom of the chute 38 is expelled by moving in a direction normal to the plane of FIG. 2.

32. As the jacketed book leaves the chute 38, it allows the limit switch LS3 to open.

33. Reopening of LS3 immediately results in deenergization of the winding of relay device R1.

34. When the piston rod of the unit DP5 reaches the end of the book pushoff stroke, it contacts and opens the limit switch LS5.

35. Opening of LS5 turns off the relay device R5.

36. With R5 off, the associated relay switch R5(6-7) opens and deenergizes the solenoid AC5.

37. Deenergization of solenoid AC5 causes the piston rod of the unit DP5 to return to its normal retracted position.

38. By retracting its piston rod, the unit DP5 allows the limit switch LS5 to close.

Closing of LS5 turns on the relay device R5.

40. R6 is off when R5 is on. Furthermore, the normally open switch between terminals 5 and 7 of the monitoring unit EE2 is closed because a jacket is present at the folding station 52. Moreover, the relay switch R8(4-1) is closed because the relay device R8 is off during automatic operation. Consequently, energizing

current flows through the series-connected relay switches R6(8-5), R5(11-9) and R8(4-1) shown in FIG. 17, and through the relay winding connected between terminals 2 and 7 of R9.

41. Although current flows through the relay winding of relay device R9, the normally closed relay switch thereof extending internally between terminals 8 and 5 does not immediately open. R9 being a time-delay relay device, a predetermined adjustable time interval elapses between the commencement of flow of energizing current through the winding of device R9 and the movement of the associated relay switches to their non-normal positions. For the duration of this interval, the current flowing through switches R6(8-5), R5(11-9), and R8(4-1) flows into the terminal 8 and out of terminal 5 of R9 and through the activating winding of clutch CL.

42. The clutch CL is initially caused to assume the engaged position by passing an energizing current through the activating winding thereof, i.e., between terminals T28 and T29 shown in FIG. 17. Once engaged, the clutch remains engaged even if the flow of energizing current is terminated. When the shaft which is driven by the clutch has performed exactly one revolution, the clutch is automatically disengaged by mechanical means. The duration of time interval during which energizing current flows through CL from R9 is sufficient to get the clutch engaged; this having been done, the rest of the clutch operation proceeds mechanically, the flow of energizing current terminating upon elapse of the time delay determined by the relay device R9.

43. With the clutch CL engaged, the main drive shaft which drives the conveyors 53 is caused to perform exactly one revolution, thereby advancing the conveyors 53 a distance of 20 inches. As a result, a blank 16 from the stack 17 is brought to the folding station 52, and simultaneously therewith a freshly formed book jacket is advanced from the station 52 to the assembly station 54.

44. Going back to the steps 40 and 41, the turning on of the relay device R9 which occurs after a jacketed book is dumped into and then expelled from the chute 38 can only take place if the monitoring unit EE2 senses the presence of a jacket at the folding station 52. In other words, when a jacketed book is dumped into the chute 38, the clutch CL will become engaged to advance the conveyors 53 by 20 inches only if a jacket is ready at the folding station 52 for advancement to the assembly station 54. Otherwise, the clutch CL will not engage and the operation of the apparatus will be interrupted so that the cause of malfunction, e.g., due to exhaustion of the stack 17, can be eliminated.

45. Returning now to step 43, the drive shaft for the conveyors 53 is provided with cam means which control the limit switches LS6 and LS7, these switches being held closed except during the last 30° of rotation of such drive shaft, i.e., the switches LS6 and LS7 open when the drive shaft reaches the 330° position.

46. When the clutch CL begins to rotate the main drive shaft, the cams on this shaft cause or allow the limit switches LS6, LS7 to close.

47. Because LS6 is closed, R16 goes on.

48. With R16 on, the associated relay switch R16(1-3) closes and current flows from supply line AT28 through switch R8(8-11), through the switch connected between terminals 5 and 7 of EE2, through R16(1-3) and through the relay winding connected in

ternally in R11 between the terminals 2 and 7.

49. Despite the flow of energizing current through the relay winding of R11, R11 does not go on immediately; instead, it goes on after elapse of a predetermined adjustable time interval. During this interval, the current flowing through relay switch R16(1-3) flows through the normally closed switch internally connecting the terminals 8 and 5 of R11, and flows through the energizing winding of cam motor CM.

50. Upon elapse of the interval determined by the time-delay relay device R11, the internal switch between the terminals 8 and 5 opens, thereby breaking this particular current path into the energizing winding of the cam motor CM.

51. Meanwhile, however, the cam motor CM has already begun to rotate. When the shaft driven by the cam motor CM reaches the 30° position, it closes the switch CS1 and assures a current path for CM even after the current path through R11 becomes interrupted. When the shaft driven by the cam motor CM reaches the 360° position, CS1 opens and arrests the motor CM. Thus, the switch CS1 assures that the shaft driven by CM will perform exactly one revolution.

52. Cam motor CM additionally controls the opening and closing of switches CS2, CS3 and CS4. When the shaft driven by the motor CM reaches the 40° position, the switch CS2 closes and energizes the solenoid AC3. The energizing current for AC3 flows not only through CS2 but also through the relay switch R10(5-8); however, the relay device R10 is off during automatic operation, i.e., the switch R10(5-8) is then closed.

53. Energization of solenoid AC3 causes the switch-over valve AC3 (FIG. 2) to activate the double-acting cylinder and piston units DP3. Energization of the solenoid AC3 causes the pressure plates 61 and 62 to move from the lower positions (FIG. 5) to the raised positions (FIGS. 6, 7). The solenoid AC3 becomes deenergized when the shaft driven by the cam motor CM reaches the 330° position; the pressure plates 61 and 62 then return to positions corresponding to the position of plate 62 in FIG. 5.

54. When the shaft driven by the cam motor CM reaches the 60° position, the switch CS3 closes and energizes the solenoid AC4.

55. Energization of solenoid AC4 causes the associated switch-over valve AC4 (FIG. 2) to activate the double-acting cylinder and piston units DP4 (FIG. 2). The folding members 59, 60 move from the positions shown in FIG. 3 to positions corresponding to that of the folding member 60 in FIG. 7.

56. When the shaft which is driven by the cam motor CM reaches the 300° position, the switch CS3 opens and deenergizes the solenoid AC4. As a result, the folding members 59, 60 return to the positions shown in FIG. 3.

57. When the shaft driven by the cam motor CM reaches the 20° position, the switch CS4 closes and energizes the winding of the relay device R6.

58. With R6 on, the switch between the terminals 5, 6 of R6 (in the current path of R9) opens and prevents renewed energization of the clutch CL. This is of course appropriate, since the one-revolution clutch CL should not be again energized until it has performed a complete revolution and automatically become disengaged. To this end, cam switch CS4 is maintained closed by the cam motor CM until the shaft driven by the motor CM reaches the 330° position. The switch

R6(8-5) then opens and thereby permits renewed energization of the clutch CL.

59. Upon completion of their respective single revolutions, the shafts driven by the one-revolution clutch CL and cam motor CM stop. A jacket is present at the folding station 54, awaiting only the infeed of an unjacketed book, and the circuit components are in the states corresponding to those at the commencement of step (1).

10 60. The attendant places a second book on the conveyor 40. Such second book trips the switch LS1, causing LS1 to assume the non-illustrated position thereof, as in step (1) above, and the entire cycle from steps (1) to (59), inclusive, is repeated.

15 61. If the attendant places the second book on the conveyor 40 too soon, so that such second book trips the switch LS1 while limit switch LS7 is still closed, then, unless steps to the contrary are taken, the second book reaches the assembly station 54 before the book jacket does, which is not desired. To avoid this, if the second book trips the limit switch LS1 while limit switch LS7 is still closed, the motor 1M (motor 50) will stop until the relay device R15 goes off at the end of one revolution of the main drive shaft for the jacket conveyors. If LS1 is tripped while LS7 is still closed, energizing current for relay device R2 will cease to arrive from switch R7(4-1), shown in FIG. 16, because no current will be flowing through the internal switch connected between terminals 8 and 6 of R16 since R15T6

20 is internally connected to R15T7 in view of the fact that R15 is on. Consequently, and since R15T7 is connected to R14T6, and since R14T6 is deenergized because R14 is off, no current can reach the relay winding of R2. Therefore, if a second book trips LS1 while LS7

25 is still closed, the motor 1M (motor 50) stops. The motor 1M cannot be started again until switch LS7 opens and then again closes, which occurs at the end of the jacket advancement cycle, i.e., when the clutch CL, 30 75 disengages. The switches PB3 to PB10 will only be operative if switch MS2 is in the "MANUAL" position thereof, with the main power switch MS1 closed.

Pressing PB3 turns R2 on to start the motor 1M until PB3 is released.

45 50 Pressing PB4 energizes solenoid AC1, causing the arms 78, 79 to move from the positions of FIG. 10 to those shown in FIG. 11. Energization of solenoid AC1 is possible because the relay switch R7(6-7) is closed, since R7 goes on as soon as the switch MS2 is put into "MANUAL" position. When PB4 is released, the arms 78, 79 return to the positions shown in FIG. 10.

Pressing PB5 energizes solenoid AC2, causing the platform 76 to tilt (see FIG. 12). Releasing of PB5 causes the platform 76 to reassume its horizontal position.

55 Pressing PB6 causes the clutch CL to become energized. Accordingly, the clutch connects the motor DM to the drive shaft for the jacket conveyors. This drive shaft performs one revolution and then stops, i.e., the pushbutton for the switch PB6 can be released immediately.

Pressing PB7 energizes solenoid AC5, thereby activating the unit DP5. Release of PB7 deenergizes solenoid AC5, causing the piston rod of the unit DP5 to assume the normal retracted position.

60 Pressing PB8 starts the cam motor CM.

The solenoids AC4, AC5 are respectively energized in response to closing of the switches PB9, PB10.

FIGS. 19 and 20 show the assembly and evacuating stations of a slightly modified jacketing apparatus. A jacketed book 25 is shown in FIG. 19 immediately upon descent onto the slightly inclined supporting plate or box 201 of a vibrating trough 200. The jacket of the book 25 is located between the pusher 203 of a piston rod 204 forming part of the cylinder and piston unit DP5 and a latch or stop 205 mounted on the upwardly extending plate or wall 202 of the trough 200. A book which is in the process of being assembled with a jacket is shown at 25a. When the pusher 203 performs a working stroke, the book 25 pivots the latch 205 counterclockwise against the opposition of a spring (not shown) so that the book 25 moves into abutment with the previously shifted book 25b of a series or row of books 25b, 25c. . . . on the supporting plate 201. The trough 200 forms part of a vibrating conveyor (including springs 206) which causes the covers and/or the jackets of books on the plate 201 to move into abutment with the wall 202 so as to insure that each jacket is in accurate register with the respective covers before the books 25b, 25c. . . are removed from the trough 200. The inclination of the plate 201 with respect to a horizontal plane and the inclination of the wall 202 with respect to a vertical plane (see FIG. 20) may be in the range of 10-15 degrees.

The latch 205 automatically returns to the upright position of FIG. 19 as soon as the book 25 moves therebeyond. This latch performs the additional function of preventing the leftmost book 25b from overturning into the path of downward movement of the next-following book. While shifting the book 25 beyond the latch 205, the pusher 203 simultaneously advances the books 25b, 25c. . . by a step in a direction away from the latch 205. The unit DP5 then retracts the pusher 203 so that the book 25a can descend onto the plate 201 as soon as the jacketing operation at the assembly station 254 is completed.

The trough 200 replaces the inclined chute 38 and stop 39 of the first apparatus.

FIG. 21 shows a portion of a third apparatus wherein successive jacketed books 25, 25b, 25c. . . are evacuated by a take-off conveyor 300 here shown as including an endless belt 301. A book 25 which descends in a chute (not shown) corresponding to the chute 38 of the first apparatus abuts against the stop 39 and one side of its jacket is adjacent to a roller-shaped tilting member 302. A modified pusher 303 on the piston rod 204 of the unit DP5 is adjacent to the other side of the jacket on the book 25. The back of the book 25 rests on the horizontal topmost portion of a ramp 308 which further includes a portion sloping downwardly toward the upper stretch of the belt 301. When the piston rod 204 performs a working stroke (arrow 204a), a strip 303a on the lower portion of the front face of the pusher 303 moves the back of the book 25 into the space below the tilting member 302 whereby the book 25 begins to slide along the sloping portion of the ramp 308 and descends onto the belt 301 to be advanced to an automatic packing machine or to a position within reach of an attendant who places jacketed books into crates, boxes or other types of receptacles, or onto a vehicle for transport to another processing station in the plant.

Without further analysis, the foregoing will so fully reveal the gist of the present invention that others can, by applying current knowledge, readily adapt it for various applications without omitting features which fairly constitute essential characteristics of the generic and

specific aspects of the above-described contribution to the art and, therefore, such adaptations should and are intended to be comprehended within the meaning and range of equivalence of the claims.

5. What is claimed as new and desired to be protected by Letters Patent is set forth in the appended claims:

1. A method of applying jackets to the covers of books, comprising the steps of converting successive sheet-like blanks into jackets each of which includes a central panel and two flaps flanking the panel; moving successive jackets to an assembly station along a first path; opening successive books so that their covers are spaced apart from the leaves; moving the thus opened books to said assembly station along a second path so that portions of the covers of a book enter between the panel and the flaps of a jacket at said station; and closing the book so that the flaps of the respective jacket are located between the covers and leaves of the thus jacketed book.

10 15 20 25 30 35 40 45 50 55 60 65 70 75 80 85 90 95

10. What is claimed as new and desired to be protected by Letters Patent is set forth in the appended claims:

2. A method as defined in claim 1, wherein the jackets moving along said first path to advance counter to the direction of movement of books along said second path.

3. A method as defined in claim 1, further comprising the steps of visually inspecting each book prior to introduction into said second path, said inspecting step comprising determining whether or not the end papers flanking the leaves adhere to the respective covers and introducing into said second path only those books

30 wherein the end papers do not adhere to the covers.

4. A method as defined in claim 1, wherein said first moving step comprises maintaining the panels of jackets in a substantially horizontal plane during travel along said first path and said second moving step comprises maintaining the covers of books in a substantially horizontal plane during travel along said second path.

5. A method as defined in claim 1, further comprising the step of moving jacketed books along a third path, including maintaining the jacketed books in a substantially vertical plane.

6. A method as defined in claim 1, wherein said converting step comprises heating the blanks in the regions where the flaps adhere to the respective central panels.

7. A method as defined in claim 1, further comprising the step of monitoring one of said paths for the presence or absence of jackets or books in said one path, and interrupting the movement of books or jackets along the other of said paths in response to detected absence of jackets or books in said one path.

8. A method as defined in claim 1, further comprising the step of maintaining the flaps in a predetermined orientation with respect to the corresponding central panels at said assembly station.

9. A method as defined in claim 1, further comprising the steps of maintaining successive jacketed books in an upright position, moving successive jacketed books from the level of said assembly station to a level therebelow, and thereupon moving the jacketed books sideways.

10. A method as defined in claim 1, wherein said closing step comprises simultaneously pivoting the covers toward the respective leaves.

11. A method as defined in claim 1, further comprising the step of shifting the jackets of successive jacketed books when the central panel of a jacket exposes portions of the respective covers.

12. A method as defined in claim 11, wherein said shifting step comprises locating successive jacketed

books in a substantially vertical plane and moving the books edgewise against a stop to thereby shift the jackets relative to the respective covers or vice versa.

13. A method as defined in claim 1, wherein said blanks are rectangular and said converting step comprises simultaneously folding two parallel marginal portions of a blank over the median portion of such blank whereby said marginal portions constitute the flaps and the median portion constitutes the panel of the resulting jacket.

14. Apparatus for jacketing books, comprising a source of sheet-like deformable blanks; means for withdrawing blanks from said source; means for converting successive withdrawn blanks into jackets wherein a central panel is flanked by two flaps; means for feeding successive jackets to an assembly station; means for transporting to said station successive books in such position that the covers of a book arriving at said station are spaced apart from the leaves and enter between the flaps and the panel of a jacket at said station; and means for closing the covers of a book at said station so that the flaps of the respective jacket are located between the covers and leaves of the thus jacketed book.

15. Apparatus as defined in claim 14, wherein said feeding means includes at least one first conveyor for moving jackets to said station in a first direction and said transporting means comprises at least one second conveyor for moving books to said station in a second direction counter to said first direction.

16. Apparatus as defined in claim 14, wherein said converting means includes means for heating the blanks in regions where the flaps adhere to the respective panels.

17. Apparatus as defined in claim 14, further comprising means for interrupting the operation of said feeding means in the absence of books on said transporting means.

18. Apparatus as defined in claim 14, further comprising means for interrupting the operation of said transporting means in the absence of jackets on said feeding means.

19. Apparatus as defined in claim 14, further comprising means for evacuating jacketed books from said assembly station.

20. Apparatus as defined in claim 19, wherein said evacuating means comprises a platform on which the books and jackets rest at said assembly station, said platform being movable between a substantially horizontal and an inclined position, and means for moving said platform between said positions whereby a jacketed book slides off said platform when the latter assumes said inclined position.

21. Apparatus as defined in claim 20, wherein said evacuating means further comprises a chute which receives jacketed books sliding off said platform.

22. Apparatus as defined in claim 21, further comprising means for removing jacketed books from said chute.

23. Apparatus as defined in claim 20, further comprising conveyor means positioned to receive jacketed books sliding off said platform.

24. Apparatus as defined in claim 14, further comprising means for moving the jackets of jacketed books into exact register with the respective covers.

25. Apparatus as defined in claim 14, wherein said transporting means comprises a plurality of successive conveyors and means for driving said conveyors at different speeds so that the speed of a book leaving a preceding conveyor increases when the book reaches the next-following conveyor.

10 26. Apparatus as defined in claim 14, wherein said withdrawing means comprises a first conveyor arranged to transport successive blanks into the range of said converting means and said feeding means comprises at least one second conveyor for moving successive jackets from said converting means to said assembly station.

20 27. Apparatus as defined in claim 14, further comprising adjustable guide means adjacent to the paths of movement of jackets and books to said assembly station.

25 28. Apparatus as defined in claim 14, wherein said converting means comprises cooperating stationary and mobile folding members for blanks and means for moving said mobile folding members with respect to the associated stationary folding members.

29. Apparatus as defined in claim 14, further comprising means for maintaining the flaps of blanks on said feeding means in a predetermined orientation with respect to the corresponding central panels.

30 30. Apparatus as defined in claim 14, wherein said closing means comprises a pair of arms movable at said station from first positions in which said arms support a jacket and the covers of a book, with the covers spaced apart from the respective leaves, to second positions whereby said arms pivot the covers against the respective leaves.

35 31. Apparatus as defined in claim 14, further comprising a book inspecting station located immediately ahead of said transporting means so that a book which has been manually inspected at said inspecting station and has been found to be satisfactory can be placed by hand onto said transporting means.

32. Apparatus as defined in claim 14, further comprising pneumatic means for temporarily holding jackets during assembly with books at said station.

33. Apparatus as defined in claim 14, wherein said feeding means and said transporting means define substantially horizontal paths for the jackets and book covers.

34. Apparatus as defined in claim 33, further comprising means for maintaining the leaves of books on said transporting means in a substantially vertical plane.

35. Apparatus as defined in claim 14, further comprising means for evacuating jacketed books sideways with respect to said assembly station.

36. Apparatus as defined in claim 14, further comprising means for cyclically operating said withdrawing, converting, feeding, transporting and closing means in a predetermined sequence.
